CLAIM

The ornamental design for toner supplying cartridge, as shown and described.

DESCRIPTION

Figure 1.1 is a front view of a toner supplying cartridge showing the new design;

1.2 is a rear view thereof;

1.3 is a top plan view thereof;

1.4 is a bottom plan view thereof;

1.5 is a left side view thereof;

1.6 is a right side view thereof;

1.7 is a top perspective view thereof;

1.8 is a bottom perspective view thereof.
